(57) **CLAIM**

The ornamental design for a refrigerator, as shown and described.

DESCRIPTION

FIG. 1 is a front perspective view of a refrigerator, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged perspective view of the claimed portion of the refrigerator, separately shown for clarity of illustration;

FIG. 9 is an enlarged front view of the claimed portion of the design refrigerator, separately shown for clarity of illustration;

FIG. 10 is an enlarged rear view of the claimed portion of the design refrigerator, separately shown for clarity of illustration;

FIG. 11 is an enlarged left-side view of the claimed portion of the refrigerator, separately shown for clarity of illustration;

FIG. 12 is an enlarged right-side view of the claimed portion of the refrigerator, separately shown for clarity of illustration;

FIG. 13 is an enlarged top plan view of the claimed portion of the refrigerator, separately shown for clarity of illustration;

FIG. 14 is an enlarged bottom plan view of the claimed portion of the refrigerator, separately shown for clarity of illustration;

(Continued)

FIG. 15 is an enlarged view of the encircled portion 15 in FIG. 1;
FIG. 16 is an enlarged view of the encircled portion 16 in FIG. 2;
FIG. 17 is an enlarged view of the encircled portion 17 in FIG. 4;
FIG. 18 is an enlarged view of the encircled portion 18 in FIG. 5;
FIG. 19 is an enlarged view of the encircled portion 19 in FIG. 6;
FIG. 20 is an enlarged view of the encircled portion 20 in FIG. 7; and,
FIG. 21 is an enlarged view of the encircled portion 21 in FIG. 8.
The even-dash broken lines illustrating portions of the refrigerator form no part of the claimed design. The dot-dash broken lines encircling enlargement portions of the claimed design form no part of the claimed design.
